ABSTRACT: A semi-airborne vehicle is disclosed driven by a surface bound propulsion unit. Extending forwardly from the surface propulsion unit is a long pylon boom having at the forward end thereof the airborne portion of the vehicle in the form of a winged body adapted to rise above the surface of the water under the control of a pilot who rides in the cockpit of the winged body. The surface propulsion unit, which is unmanned, never leaves the surface. In one preferred form, the surface unit is water bound, and the winged body, which utilizes aero-dynamic lift and is capable of limited roll and pitch, includes a hull and a wing supported on said hull for free pivotal movement about the pitch axis.

U.S. PATENT 3,522,785
SEMAIRBORNE VEHICLE

FIELD OF THE INVENTION

This invention relates to a semiairborne vehicle having partial degrees of freedom of flight but in which the propulsion unit is surface bound.

DESCRIPTION OF THE PRIOR ART

The prior art shows waterborne craft of the hydroplane type in which high speeds are obtained by achieving planing speeds.

Also shown in the prior art are various forms of hydrofoil type craft which are supported at cruising speeds by airfoil-shaped members which ride submerged in the water to produce hydrodynamic lift.

Also shown in the prior art are semiairborne craft in which a water propulsion device is suspended by various complex sliders or linkages beneath the basic body of the craft, giving a small amount of vertical freedom to lift the craft aerodynamically but with poor adaptability to wave action.

SUMMARY OF THE PRESENT INVENTION

The object of the present invention is to provide a vehicle which achieves partial degrees of freedom of flight, with a reasonable degree of stability. A long pylon boom extends forwardly from a surface-bound propulsion unit which pushes a winged body which may rise above the surface to the extent permitted by the length of the boom, under pilot control utilizing aerodynamic lift. In the preferred form illustrated, the airborne portion of the vehicle includes a hull, and a wing portion mounted on said hull for free pivotal movement about the pitch axis. The wing portion includes ailerons and elevator. The airborne portion is capable of limited roll and pitch maneuvers and execution of turns using wing lift, as done by an airplane in free flight. The surface-bound propulsion unit is, in my preferred form, a waterborne unit.

BRIEF DESCRIPTION OF THE DRAWING

FIGURE 1 is a plan view of a preferred form of semiairborne vehicle;

FIGURE 2 is a side elevational view of the vehicle of **FIGURE 1**;

FIGURE 3 is a front elevational view.

DESCRIPTION OF THE PREFERRED EMBODIMENT

Illustrated in **FIGURES 1-3**, is my new semi-airborne craft embodying the basic concept of the present invention. The craft illustrated comprises a water-surface-bound propulsion unit **10** comprising an auxiliary planing hull **12** powered by a known form of engine, such as a gasoline motor **14** for driving a water propeller **15** which may be supported on a rudder **17** or other shaft. Alternatively, the water-surface-bound propulsion unit may be propelled by an air propeller.

Extending forwardly from the water propulsion unit **10** is a long pylon boom **16** having a winged body **20** secured to the forward end thereof. The winged body **20** comprises a planing hull or fuselage **21** having a forward rudder **35** for waterborne steering. The hull includes a cockpit **22** equipped with necessary and known forms of controls. A pair of struts **25** project upwardly from the fuselage **21** on which the wing **27** is supported for free pivotal movement about the pitch axis. Ailerons **28** and **29** are provided at the trailing edge portions of the wing **27** for lateral balance and roll control purposes.

Extending rearwardly from the freely pivotable wing **27** are a pair of elevator booms **31** for supporting at the rearward ends thereof a fixed elevator stabilizer surface **32** having a hinged controllably-movable elevator surface **33** for pitch control purposes.

Suitable cables not shown extend from the cockpit through the boom **16** to the water-surface propulsion unit **10** to enable the pilot in the cockpit **22** to control the starting, stopping and

speed of the propulsion engine **14** and also the angular orientation of the water rudder **17** or shaft on which the propeller **15** is supported.

The cockpit **22** is also equipped with known types of flying or steering controls to enable the pilot to manipulate the ailerons **28** and **29**, the elevator surface **33**, and the forward rudder **35**.

In operation, turns are made in the airborne mode by banking the craft aerodynamically with the ailerons **28** and **29**.

Landings are made using airplane techniques by throttling back and progressively lifting the elevator surface **33** to obtain minimum flying speed at touchdown.

In flight, if the craft approaches excessively high angles, the boom **16** will pull up the auxiliary planing hull **12** and the planing hull **12** will tend to stall hydrodynamically, thereby slowing the craft. This will prevent excessive or dangerously high angles, even though the pilot, due to inexperience or inattention, is not alert to proper management of the height of the airborne portion of the vehicle.

It will be seen that I have provided a vehicle in which the pilot and passenger-carrying portion is supported by aerodynamic lift and controlled by aerodynamic forces. However, the craft never becomes entirely airborne. Thus, the risks assumed by the pilot and passengers are substantially less

than in a fully airborne craft. Also, since in the preferred waterborne form of semiairborne vehicle the drive propeller remains in the water, the hazards created by an air propeller are avoided.

The craft of the present invention may be used for pleasure purposes, or for flight training purposes, or for high-speed travel over the water.

While the craft has been described in its preferred form as a waterborne-airborne craft, supported by a combination of aerodynamic and hydrodynamic forces, the surface-bound portion of the craft could be designed for ground travel, as distinguished from water travel. Also, while the preferred form shows the use of a pivotal but otherwise conventional fixed wing, it is contemplated that the craft may be designed with an autorotating rotary wing to provide the lift in place of the wing. Other types of wing may also be used.

The craft described provides a close approach to the sensation of true flight, yet it may be powered by an outboard type motor or other readily available power plant of the non-aircraft type. The winged body may achieve appreciable height above the surface, although the propulsion unit remains surface-bound. Large unbalanced forces and moments are avoided since the thrust vector and the centers of lift and drag of the airborne body lie close to its center of gravity.

Attention is also called to the fact that by pivotably mounting the wing **27** in the manner shown, the wing angle of attack becomes self-adjusting to a constant value with respect to the airstream, independently of the attitudes of the winged body. This feature overcomes the unstable lift gradient which a simple rigidly attached wing would tend to exert on this type of craft.

I claim:

1. a semiairborne vehicle comprising:
  - (a) a surface bound propulsion unit;
  - (b) a winged vehicle supportable by aerodynamic lift;
  - (c) said winged vehicle including a hull and a wing pivotally mounted on said hull for free pivotal movement about the pitch axis with provision for stability of aerodynamic angle of attack independently of vehicle attitude; and
  - (d) an elongated member rigidly connecting said surface propulsion unit and said hull of said winged vehicle in tandem arrangement.

2. A vehicle according to claim 1 characterized in that said elongated member extends forwardly from said surface bound propulsion unit and is rigidly connected at its forward end to the hull of said winged vehicle.

3. A vehicle according to claim 2 characterized in that the surface propulsion unit is a water planing vehicle having a propeller and an engine for driving said propeller.

4. A vehicle according to claim 3 characterized in that said propeller is a water propeller.

5. A vehicle according to claim 4 characterized in that said winged vehicle includes aileron surfaces for roll control and elevator surface for pitch control.

6. A vehicle according to claim 5 characterized in that said hull includes a rudder for waterborne steering.

7. A vehicle according to claim 6 characterized in that said propulsion unit includes a rudder.
